UNITED STATES PATENT OFFICE.

FRANK H. CALDWELL, OF LOOKOUT MOUNTAIN, TENNESSEE, ASSIGNOR TO THE CAHILL IRON WORKS, OF CHATTANOOGA, TENNESSEE, A CORPORATION OF TENNESSEE.

DESIGN FOR A SINK.

No. 40,088.

Specification for Design.

Patented June 22, 1909.

Application filed February 20, 1909. Serial No. 479,282. Term of patent 14 years.

To all whom it may concern:

Be it known that I, FRANK H. CALDWELL, a citizen of the United States, residing at Lookout Mountain, in the county of Hamilton, State of Tennessee, have invented a new, original, and ornamental Design for Sinks, of which the following is a specification, reference being had to the accompanying drawing, forming part thereof.

The figure is a perspective view of a sink showing my new design.

I claim:

The ornamental design for sink, as shown.

FRANK H. CALDWELL.
